UNITED STATES PATENT OFFICE.

ABRAHAM SCHACHAT, OF BROOKLYN, NEW YORK, ASSIGNOR TO SLOCUM, AVRAM & SLOCUM, LABORATORIES, INC., OF NEW YORK, N. Y., A CORPORATION OF NEW YORK.

SQUARE.

1,306,722.

Specification of Letters Patent. Patented June 17, 1919.

Application filed April 25, 1917, Serial No. 164,423. Renewed May 9, 1919. Serial No. 295,925.

To all whom it may concern:

Be it known that I, ABRAHAM SCHACHAT, a citizen of the United States, residing at Brooklyn, city of Greater New York, State 5 of New York, have invented certain new and useful Improvements in Squares, of which the following is a specification.

My invention relates to squares, more particularly adapted for use by tool makers, 10 and has for its primary object to provide an article of this character wherein the blade of the device is adjustable to some extent with respect to its stock, and has associated therewith indicating mechanism, whereby variations 15 in angles from the 45° angle may be detected instantly, and the amount of variation in degrees may be determined with accuracy.

My improved construction also embodies 20 certain minor details, as will be pointed out hereinafter more definitely, reference being had to the accompanying drawing, in which:—

Figure 1 is a perspective view of my improved device, the blade being shown partly 25 broken away.

Fig. 2 is a face view of the same, one of the cover plates being removed.

Fig. 3 is a view similar to Fig. 2 with one 30 section of the stock removed.

Fig. 4 is a sectional view through the stock taken on the line IV—IV of Fig. 2.

Fig. 5 is an elevation of the device, looking 35 at the end of the stock to which the blade is attached.

Fig. 6 is a transverse sectional view taken on the line VI—VI of Fig. 2.

Fig. 7 is a detail sectional view taken on the line VII—VII of Fig. 3.

Similar numerals of reference denote 40 corresponding parts in the several views.

In the said drawing the reference numeral 1 denotes the blade of the square, which is attached by means of a pivot pin 2 to the 45 stock, the latter being formed in two sections 3 fastened together by means of screws 4, this fastening means being supplemented by dowel pins 5, which position the two parts 3 with respect to each other before the screws 50 4 are inserted in position. The outer face of each of the sections 3 of the stock is recessed at 6, and at its side edges is rabbeted to receive a sliding cover plate 7 correspondingly shaped at its edges, said cover plate 55 terminating at its inner end on the arc of a

circle struck from the pivot pin 2 and somewhat short of the recess 6, as best seen in Fig. 1, thereby to disclose a degree scale 8 marked upon the inclined face of the recess 6 at that end of the device. The ends of 60 the pivot pin 2 are squared at 9, and each has mounted thereon a pointer 10 which extends in the space between its cover plate 7 and its section 3 of the stock to the scale 8, so that movements of said pointer will be 65 shown on the said scale in a manner readily understood. It will be understood that the blade 1 of the device is fixed to its pivot pin 2, and also fixed to each side of said blade is one end of a coiled spring 11, the other end 70 of which is fixed to its section 3 of the stock, as shown in Fig. 4. These springs are arranged so that they will exert their tension between the blade 1 and the stock to cause said blade to assume the position with 75 respect to the stock shown in Fig. 2, that is to say, at a slightly acute angle with respect thereto, the inner edge of the blade abutting a shoulder 3^a on the stock to limit said movement, as best seen in Fig. 3. With 80 the parts in this position the pointers 10 will be moved to their extreme of movement to the acute angle side of the 90° position, as shown in Fig. 2. The blade 1 is capable of movement to a corresponding degree to the 85 obtuse angle side of the right angle position, and is limited in its movement in that direction by the inner lower end thereof coming in contact with the shoulder 3^a, in a manner similar to its contact under the acute angle 90 movement.

In order to maintain the blade in a position at a true right angle to the stock, I provide an aperture 12 in said blade, which is adapted to register accurately with corresponding apertures 13 in the sections 3, so that upon the insertion of a pin 14 accurately fitting said apertures, the blade 1 will be maintained at a true right angle with respect to the stock, it being understood that 95 the cover plates 7 are similarly apertured at 15 in register with the apertures 13 to receive said pin 14. In each of the sections 3 I also provide a screw-threaded aperture 16, receiving a headed screw 17, adapted to be 100 brought into contact with the face of the blade 1, whereby the latter may be clamped in any adjusted position away from the right angle position when desired, it being understood that the cover plates 7 are 105 110

apertured similarly at 18 to receive said screw 17.

In using the device, it will be understood that when it is desired to ascertain just how much a piece of work is out of square, the same may be determined with accuracy by applying my improved square thereto, the springs 11 automatically positioning the blade 1 against the work, and the variation in degree will be indicated upon the scale 8.

When the device is desired to be used as a true square, the insertion of the pin 14 will fix the parts in such position, and when it is desired to clamp the blade 1 in any of its positions of adjustment out of true square position, this may be accomplished by means of the set-screw 17. A pointer 10 is provided on each side of the stock so that a scale reading may be had from either face of the device.

In the outer end of the stock I provide an aperture 19 for the purpose of receiving the pin 14 when the same is not used to retain the blade 1 in the right angle position. In one of the sections of the stock 3, I provide two screw threaded apertures adapted to receive therein small screws 20 with 45° points, which coöperate with cut-away portions 21 in the blade 1 to limit the movement of said blade and prevent it from hitting the stock, as shown in detail in Fig. 7. In other words, they act as stops to limit the maximum movement of the blade 1 in either direction. It will be understood, however, that neither of these features is essential to the effective operation of the device otherwise.

Having thus described my invention, what I claim as new and desire to secure by Letters Patent, is:—

1. A square, comprising a stock, a blade pivoted thereto and capable of limited adjustment to either side of a 90° angle with respect to said stock, said stock and blade having apertures adapted to register when

the two are at a 90° angle, a pin removably disposed in said aperture to retain said stock and blade in said adjusted position, a spring interposed between said stock and blade for maintaining said blade at the inner extreme of its pivotal adjustment by tension in that direction when not retained by said pin, and a pointer and scale disposed between the parts to indicate the degree of variation from said 90° angle.

2. A square, comprising a two-part stock, a blade pivoted therebetween and capable of adjustment to either side of a 90° angle with respect to said stock, a pointer fixed to said blade and coöperating with a scale on said stock to indicate the degree of variation from said 90° angle, and a removable plate adapted to cover all of said pointer except its free end which coöperates with said scale.

3. A square, comprising a stock, a blade pivoted thereto and capable of adjustment to either side of a 90° angle with respect to said stock, a pointer disposed in a recess in said stock and fixed to said blade and coöperating with a scale on said stock to indicate the degree of variation from said 90° angle, and a cover plate having sliding engagement with said stock to cover said recess and pointer, said plate when in its adjusted position terminating short of the scale on said stock and short of the free end of said pointer indicating on said scale.

4. A square, comprising a stock, a blade pivoted thereto and capable of adjustment to either side of a 90° angle with respect to said stock, and coiled springs upon opposite sides of the pivot of said blade and engaging said blade and stock respectively to maintain said blade normally at the inner extreme of its pivotal adjustment by tension in that direction.

In testimony whereof, I hereunto set my hand this 23d day of April, 1917.

ABRAHAM SCHACHAT.
